DESIGN FOR A BROOCH OR SIMILAR ARTICLE

Louis Mazer, New York, N. Y.

Application October 29, 1941, Serial No. 103,935

Term of patent 3½ years

To all whom it may concern:

Be it known that I, Louis Mazer, a citizen of the United States and a resident of New York city, in the county of New York and State of New York, have invented a new, original, and ornamental Design for a Brooch or Similar Article, of which the following is a specification, reference being had to the accompanying drawing, forming part thereof, and in which

Fig. 1 is a front elevational view of a brooch or similar article showing by new design, and Fig. 2 is a side elevational view thereof.

I claim:

The ornamental design for a brooch or similar article, substantially as shown.

LOUIS MAZER.
